UNITED STATES PATENT OFFICE.

KASPAR FREULER, OF ZÜRICH, SWITZERLAND.

COLLAPSIBLE STRETCHER.

SPECIFICATION forming part of Letters Patent No. 740,002, dated September 29, 1903.

Application filed August 4, 1902. Serial No. 118,407. (No model.)

To all whom it may concern:

Be it known that I, KASPAR FREULER, a citizen of the Republic of Switzerland, residing at Zürich, in the Republic of Switzerland, (whose post-office address is 120 Birmensdorferstrasse, Zürich,) have invented new and useful Improvements in Collapsible Stretchers, (for which I have made application for patents in Switzerland, No. 29,514, May 21, 1902; Germany June 21, 1902; Austria June 21, 1902; Hungary July 2, 1902; France July 5, 1902; Belgium June 21, 1902; Denmark July 7, 1902; Spain July 7, 1902; Sweden July 8, 1902; Italy July 8, 1902; Norway July 9, 1902; Portugal July, 10, 1902; England July 12, 1902, No. 15,559,) of which the following is a specification.

My invention relates to improvements in that type of collapsible stretchers in which the frame is formed in lazy-tongs fashion.

The object is to increase the carrying power and at the same time reduce the weight of such stretchers and to cause the props of the head - rest in extending or collapsing the stretcher to rise or fall automatically and so as to take up as little space as possible when collapsed. I attain these objects by the means illustrated in the accompanying drawings, in which—

Figure 1 is a side view of a stretcher extended, and Fig. 2 of the same about half collapsed.

Similar letters refer to similar parts throughout the several views.

In carrying out my invention and referring to the figures generally, each frame side consists of two or more lazy-tongs, in the present instance two, *a* and *b*, hinged together and placed upon each other, the tongs *a* being distinguished from *b* in Fig. 1 by being shaded. The said lazy-tongs are hinged together where they cross each other, their ends *c* being jointed at *e* to the corner-pieces *d*, formed of angle-iron, and the ends *f* by means of headed pins *g*, guided in slots *h*, formed in the said corner-pieces as well as the ends *i*. In sliding the tongs end pins *g* upward they abut against the end of the slot *h*, in which position they

are retained by the hooks *l*, while the stretcher remains extended. 50

To the corner-pieces *d* are pivoted at *m* the handles *n* and to the latter the rails *o*, the free ends of which are formed into eyes adapted to be placed onto the pins *g* of the tongs ends *i*. At the head of the stretcher rails *q* are connected with the tongs ends *i*, guided in straps *r*, which rails serve to hold the head portion of the stretcher-cloth and are adapted to rise when extending and to fall when collapsing the stretcher. These rails, as well as 55 the upper tongs ends, carry headed pins *s*, onto which the stretcher-cloth is hooked.

In collapsing the stretcher the hooks *l* and the rails *o* are removed from the pins *g* and the tongs pushed together, after which the 60 handles *n* are turned inward.

The carrying power of the stretcher is increased by the increased number of cross-levers (tongs parts) employed and connected together at short distances apart from each other, which levers may be made of such light material that, as practice has proved, a stretcher weighing from seven to eight kilos will have a carrying power of at least one hundred and fifty kilos. In collapsing the 75 stretcher the said cross - levers, being very slender, will take up comparatively very little room. By lengthening the said corner-pieces the described stretcher system may also be used as camp-bed or the like. 80

What I claim as my invention, and desire to secure by Letters Patent, is—

1. A folding stretcher comprising two pairs of corner - posts, a series of lazy - tongs sections connecting the posts of each pair and pivoted thereto at their upper corners, the lower end of each lazy-tongs section being arranged to slide in a vertical slot in the post, and a pair of vertical rods adapted to support a head - rest, said rods being slidably 85 mounted on the posts at the head end of a bed and pivotally connected at their ends to the lower ends of the lazy - tongs sections whereby the extension of the bed causes said rods to be projected above the upper 90 ends of said posts. 95

2. A folding stretcher or bed, a head-post having vertical guides and a vertical rod adapted to support a head-rest vertically slidable in said guides.

5 3. A folding stretcher or bed, a head-post comprising a vertical standard adapted to support the frame and having a longitudinal socket therein, a head-rest-supporting rod reciprocable in said socket and having means

on the upper end thereof for attaching a head-rest, and means for holding said rod in raised position.

In witness whereof I have hereunto set my hand in presence of two witnesses.

KASPAR FREULER.
